UNITED STATES PATENT OFFICE.

CORWILL JACKSON, OF KALAMAZOO, MICHIGAN.

TAMPER.

1,361,261.

Specification of Letters Patent. Patented Dec. 7, 1920.

Application filed December 20, 1919. Serial No. 346,210.

To all whom it may concern:

Be it known that I, CORWILL JACKSON, a citizen of the United States, residing at the city and county of Kalamazoo, State of Michigan, have invented certain new and useful Improvements in Tamers, of which the following is a specification.

This invention relates to improvements in tamers.

10 My improvements are especially designed by me for embodiment in tie tampers and the embodiment illustrated is especially adapted for that purpose. My improvements are, however, readily adapted for and 15 of advantage for use in other relations.

The main objects of this invention are:

First, to provide an improved tamper which is of large capacity in that it enables the performance of a large amount of work 20 with comparatively little effort on the part of the user.

Second, to provide an improved tamper which is very durable in use.

Third, to provide an improved tamper 25 for use in tamping ties and the like which is effective in tamping the earth under the ties providing a bed which is not likely to settle or have untamped portions in which the material is easily loosened by means of 30 water or the like.

Fourth, to provide an improved motor 35 driven tamper in which the parts are compact in structure and arrangement and not likely to become inoperative or get out of repair in use.

Further objects, and objects relating to structural details, will definitely appear from the detailed description to follow.

I accomplish the objects of my invention 40 by the devices and means described in the following specification. The invention is clearly defined and pointed out in the claims.

A structure which is a preferred embodiment of my invention is clearly illustrated 45 in the accompanying drawing forming a part of this specification, in which:

Figure I is a side view of a tamper embodying the features of my invention, the tamping bar being broken away.

50 Fig. II is a detail view mainly in section on a line corresponding to line 2-2 of Fig. I.

Fig. III is a central vertical section on a line corresponding to line 3-3 of Fig. II, 55 the tamping bar being shown in full lines.

Fig. IV is a detail view on a line corre-

sponding to line 4-4 of Fig. II, showing the arrangement of the unbalancing weight on the shaft.

Fig. V is a plan view of the tamping bar, 60 a portion being broken away.

Fig. VI is a vertical section through the tamping bar or tool holder on a line corresponding to line 6-6 of Fig. III.

In the drawing similar reference characters refer to similar parts throughout the several views, and the sectional views are taken looking in the direction of the little arrows at the ends of the section lines.

Referring to the drawing:

I provide a casing 1 on which the motor designated generally by the numeral 2, is mounted. The armature 3 of the motor is mounted upon the shaft 4 having bearings 5 in the ends of the casing. This shaft is 75 provided with a pair of unbalancing weights 6 disposed at the ends thereof and near its bearings. The casing is preferably cylindrical in form, as illustrated. On its under side, the casing is provided with a 80 tangentially disposed tool or tamping bar holder 7 having a socket 8 for the tamping bar 9. The tool holder is disposed centrally of the casing.

The tool or tamping bar is provided with 85 opposed notches or recesses 10 engaged by the staple-like retainer 11 passed through the holder and held therein by means of the cotter pin 12. This retains the tamping bar for limited, reciprocating movement 90 within the holder so that vibrations of the casing are imparted thereto as blows, the casing constituting an impact member for the tool or tamping bar.

The casing is provided with a handle 13 95 having spring portions 14 therein, the handle being of bail-like form, the arms 15 of the handle being connected to the ends of the casing at 16. The handle is provided with a second grip or hand-piece 17.

With the parts thus arranged, the rotation of the shaft 4 vibrates the casing and this vibration is imparted to the tool or tamping bar in the holder providing a highly efficient implement for the tamping of ties and the like, the tamper enabling the performance of a large amount of work with little effort on the part of the operator and the tamping being effected in a superior manner, that is, the earth may be rapidly and uniformly tamped and settled under the ties and about the same.

I have illustrated and described my improvements in two embodiments which I consider very satisfactory. I have not attempted to illustrate or describe various other modifications or embodiments which I contemplate as I believe the disclosure made will enable those skilled in the art to which my invention relates to embody or adapt the same as may be desired.

10 Having thus described my invention, what I claim as new and desire to secure by Letters Patent, is:

1. In a structure of the class described, the combination of a casing having a tangentially disposed tool holder on its under side, a shaft provided with bearings in the ends of said casing and having unbalancing weights at its ends, a driving motor for said shaft disposed centrally within said 15 casing between said unbalancing weights, a handle comprising spring members connected to the ends of said casing, and a tool having a limited reciprocating movement in said holder.

2. In a structure of the class described, the combination of a casing, a shaft provided with bearings in the ends of said casing and having unbalancing weights at its ends, a driving motor for said shaft disposed centrally within said 20 casing between said unbalancing weights, a handle comprising spring members connected to the ends of said casing, and a tool having a limited reciprocating movement in said holder.

25 3. In a structure of the class described, the combination of a casing, a shaft provided with bearings in the ends of said casing and having unbalancing weights at its ends, a driving motor for said shaft disposed centrally within said casing between said unbalancing weights, a handle comprising spring members connected to the ends of said casing, and a tool mounted on the under 30 side of said casing and centrally thereof.

35 4. In a structure of the class described, the combination of a casing having a tangentially disposed tool holder on its under side, a shaft having an unbalancing member thereon provided with bearings in the ends 40 of said casing, a driving means for said shaft, a resilient handle connected to the ends of said casing, and a tool having a limited reciprocating movement in said holder.

45 5. In a structure of the class described, the combination of a casing, a shaft having an unbalancing member thereon provided with bearings on said casing, a driving means for said shaft, a resilient handle connected to the ends of said casing, and a tool mounted on said casing for limited reciprocating movement whereby it receives the impact of the casing.

55 6. In a tamper, the combination of a casing, a shaft provided with bearings in the ends of said casing and having unbalancing

weights at its ends, a driving motor for said shaft disposed centrally within said casing between said unbalancing weights, a handle comprising spring members connected to the ends of said casing, and a tamping bar tangentially mounted on said casing.

6. In a tamper, the combination of a shaft having an unbalancing member thereon, a driving motor therefor, a casing, a tool holder on said casing, a tool having a limited reciprocating movement in said tool holder whereby it receives the impact of the casing, and a handle having resilient connection to said casing.

7. In a tamper, the combination of a shaft having an unbalancing member thereon, a driving motor therefor, a casing, a tool holder on said casing, a tamping bar having a limited reciprocating movement in said 75 tool holder whereby it receives the impact of the casing, and a resilient handle.

8. In a tamper, the combination of a shaft having an unbalancing member thereon, a driving means therefor, a casing, a tamping bar mounted on said casing for limited movement thereon and to receive the impact of the vibrations thereof, and a handle having a resilient connection to said casing.

9. In a tamper, the combination of a shaft 85 having an unbalancing member thereon, a driving means therefor, a casing, a tamping bar mounted on said casing for limited movement thereon and to receive the impact of the vibrations thereof.

10. In a structure of the class described, the combination of a shaft having an unbalancing means, a casing having bearings for said shaft, a tool mounted on said casing for limited movement thereon and so that 95 it receives the impact of the vibrations of the casing, and a handle having a resilient connection to said casing.

11. In a structure of the class described, the combination of a motor, a casing, vibrating means for said casing, a tool loosely mounted on the casing to receive the impact of the vibrations thereof, and a handle having resilient connections to said casing.

In witness whereof, I have hereunto set 105 my hand and seal in the presence of two witnesses.

CORWILL JACKSON. [L. S.]
